HANS DRATSCHKE, OF BROOKLYN, NEW YORK.

GAME APPARATUS.

1,374,991.

Specification of Letters Patent. Patented Apr. 19, 1921.

Application filed July 23, 1920. Serial No. 398,525.

To all whom it may concern:

Be it known that I, HANS DRATSCHKE, a citizen of the Republic of Germany, residing at Brooklyn, county of Kings, and State 5 of New York, have invented certain new and useful Improvements in Game Apparatus, of which the following is a specification.

My invention relates to an apparatus for playing a game which will afford entertainment and at the same time develop the players' skill, particularly in the judging of distances. The invention comprises a board 10 or table and an adjustable striker for hitting certain objects or counters on said table.

Two satisfactory embodiments of my invention will now be described with reference to the accompanying drawings, in which Figure 1 is a side elevation of one form of my invention; Fig. 2 is a plan view thereof; 20 Fig. 3 is a partial detail elevation, looking in the direction of the arrow 3 in Fig. 1, and drawn upon an enlarged scale; Fig. 4 is an enlarged vertical section on line 4—4 of Fig. 1; Fig. 5 is a partial side elevation of 25 another form of my invention; and Fig. 6 is a vertical section on line 6—6 of Fig. 5.

The apparatus illustrated comprises a central leg or support 10 having a reduced upper portion 10' to which is secured the 30 table top or board 11, preferably in a rigid manner. This board is represented as of circular shape, and provided with a plurality of openings 11', which I deem best to place irregularly, at varying distances from the center. The board is divided into two fields by a diametrical division which may be formed by a line 11'', or the same effect may be obtained by coloring the two halves of the board differently. The board has a 35 central circular field or disk 12, and preferably also a central rod or pin 13 which may be decorated with a flag.

Mounted rotatably about the vertical axis of the support 10 is a carrier or guide 14, 45 provided with an eye 14' surrounding the reduced portion 10' and normally resting on the upper end of the body of the support 10. This carrier is provided with two spaced longitudinal guides 15, approximately radial with reference to the board 11 and to the support 10, 10', the outer end of the carrier having a leg or prop 16 adapted to rest on a supporting surface as indicated and also forming a handle for moving the carrier 50 around the central support and for

moving said carrier up along the reduced portion 10'.

Between the guides 14, 15 is arranged to move the slide 17 provided at its inner portion with a projection or pin 18 having a knob or head 18' forming a striker as set forth hereinafter, while the outer end of the slide 17 carries an aiming device consisting of a stud 19, a finger 19' pointing toward the center of the apparatus, and preferably a notched sight 19'' or other suitable sight as shown best in Fig. 3. A special relation is observed in proportioning the dimensions of the several parts, viz: The distance between the point of the finger 19' and the center of the striker 18' is made equal to the radial distance from the periphery of the central field 12 to the outer periphery of the disk or board 11. From this it follows that whatever adjustment is given to the slide 17 inwardly or outwardly along the guide 14, 15, the distance from the point of the finger 19' to the outer periphery of the board 11 (indicated at *a* in Fig. 2) will always be equal to the radial 70 distance from the center of the striker 18' to the periphery of the central field 12 (also indicated at *a* in Fig. 2).

The apparatus further comprises suitable objects or counters 20, say of peg-like character, adapted to insert in the holes 11', as shown in Fig. 1, and preferably provided with upwardly-extending pins or flagstaffs 20', of less height than the central rod 13. The counters 20 are generally removable, 85 but this is not essential, it being sufficient that the position of a counter shall change visibly when the lower end of the counter, which preferably projects below the board 11, is hit by the striker 18'. Of course the 90 counter portion immediately above the board 11 is wider than the respective opening 11', so that the counter may not drop through.

While the apparatus may be used in various ways, I will for the purpose of illustration give an outline of a game which may be played with this apparatus.

The game is played by two players or two groups of players, each having counters 20 100 representing ships, if a naval game is intended, or regiments, batteries, etc., if a game representing war on land is to be played. While the position of the openings 11' is quite irregular, they are of equal num- 110

ber (say, twenty) in each of the halves of the board. The counters 20 are inserted into all or some of the openings 11', as may be agreed. Then each player or 5 each side in turn, takes a "shot," as follows: The player adjusts the carrier 14, 15 circumferentially to bring the sight 19" into line with the pin 20' on the counter 20 and with the central rod 13, see Figs. 2 and 3, 10 the prop 19 being used as a handle during this operation. Then, looking from above (so that he cannot see the striker 18, 18' concealed under the board), the player adjusts the slide 17 in or out until in his 15 opinion the distance from the point of the finger 19' to the edge of the board 11 is equal to the distance from the counter or marker 20 aimed at, to the periphery of the central field 12. Thereupon the player, 20 holding the props 16, lifts the carrier 14, 15 with the slide 17 and striker 18, 18' bodily toward the board, the eye 14' sliding upwardly along the reduced portion 10' of the support 10. Now, if the player has 25 gaged the distance correctly, the striker 18, 18' will have been brought into registry with the downwardly-projecting end of the counter or marker 20, as shown in Fig. 1, so that upon lifting the carrier 14, 15 as 30 described, the striker will come in contact with the said counter 20, either throwing it out of its opening 11', or at least moving it sufficiently to indicate that a "hit" has been registered. If however, the distance 35 was not judged properly, the striker when lifted will not come in contact with the counter 20, and the unchanged position of the latter will indicate a "miss." The objects or counters may be removed from the 40 board when hit, and the game continued until one side has lost all its counters, or until a predetermined number of "points" has been reached by the winning side, the manner of scoring and the other rules for 45 playing the game being of course immaterial to my invention.

In Figs. 5 and 6 I have shown another construction which dispenses with the necessity for moving the carrier and the prop 50 16 upward to lift the striker 18, 18'. According to the construction, the lateral guides 15' of the carrier have their outer ends extending beyond the base or body 14 of the carrier, and at these projecting ends 55 are located two alining pins 21 extending into longitudinal slots 17" in the sides of the slide 17'. The guides 15' do not overlap the slide 17', so that the latter is free to swing on the pivot formed by the pins 21. 60 The circumferential and the radial adjustment of the slide carrying the aiming device and the striker, are the same as in the form of construction first described, but the manipulation for moving the striker upwardly is much simpler, and consists in de- 65

pressing the outer end of the slide 17', as indicated by the arrow at the sight of Fig. 5, which operation will cause the slide to swing on the horizontal pivot 21 and move the striker 18, 18' upwardly to engage the counter 20 if the player has made the correct adjustment.

It will be understood that the circumferential movement of board and striker is a relative one, and while I prefer to have 75 the board stationary and the striker adjustable circumferentially, the same result may be obtained in other ways. Various modifications may be made without departing from the nature of my invention as set 80 forth in the appended claims.

I claim:

1. A game apparatus comprising a circular board carrying objects to be hit, an aiming device movable relatively to the board 85 around the center thereof and also movable in and out, and a striker movable in unison with said aiming device circumferentially and radially and also adapted to be moved toward the board to hit objects thereon. 90

2. A game apparatus comprising a circular board carrying objects to be hit, an aiming device movable relatively to the board around the center thereof and also movable in and out, and a striker movable in unison 95 with said aiming device circumferentially and radially and also adapted to be moved toward the board to hit objects thereon, the distance between the striker and the aiming device being equal to the distance from the central portion of the board to the periphery thereof. 100

3. A game apparatus comprising a board carrying objects to be hit, a striker arranged under the board so as to be concealed thereby and movable toward the board to hit objects thereon, and an aiming device arranged clear of the board so as to be visible, said striker and aiming device being connected to move in unison inwardly or outwardly and also laterally. 105

4. A game apparatus comprising a board carrying objects to be hit, a carrier movable relatively to said board around the center thereof, a slide movable on the carrier 115 toward and from such center, a striker carried by the inner portion of the slide and adapted to be moved into contact with the objects on the board and an aiming device carried by the outer portion of the slide. 120

5. A game apparatus comprising a circular board having a central field and provided exteriorly of said field with apertures to receive objects to be hit from below, a striker movable under the board into registry and into contact with such objects, and an aiming device located exteriorly of the board and connected to move in unison with the striker, the distance between said aiming device and the striker being equal to the dis- 125 130

tance from the periphery of the central field to the edge of the board.

6. A game apparatus comprising a board having perforations and movable objects projecting therethrough beneath the board, a striker movable under the board, into registry and into contact with the downwardly-projecting portions of such objects,

and means connected with the striker and arranged clear of the board, for adjusting 10 the striker to different positions and hitting said objects with such striker.

In testimony whereof I have affixed my signature.

HANS DRATSCHKE.
